CHARLES P. MADSEN, OF CROTON-ON-HUDSON, NEW YORK.

SYSTEM OF SOUND GENERATORS.

Application filed December 7, 1927. Serial No. 238,318.

This invention relates to a system of sound generation primarily adapted to the reproduction of sounds of audible frequency of which phonographs and radio loud speakers are types. It may also be used in the direct production of sound as in stringed musical instruments, electrically operated organs and the like.

In apparatus now employed, the motion is alternating or oscillating; that is, it moves in its travel through a zero point; whether the application be to a diaphragm, a cone or other body. This motion imparts the sound-producing vibrations but with a reduced effect for the reason that the present systems are neutral and a great part of the energy is taken up in lost motion and in initiating the vibratory action due to the inherent elasticity or compressibility of the material. By a neutral system is meant one not initially under compression or tension or one having a slight stress at a point or points remote from the point of actuation.

My invention involves the principle of placing the entire system under a considerable stress and carrying that stress to or as near the point of actuation as possible. This stressing of bodies is well known to makers of musical instruments and all such bodies are under initial stress so that in applying my invention to reproducers, I secure great brilliance and detail of reproduction combined with large volume.

An advantage accrues in the stressed system of my invention in that where the sound generator is placed under initial stress, such as might be compression and parts other than the generator are under tension the actuating motion is applied in the direction of the strain and all lost motion and a large degree of the compressibility or give of the entire system is taken up so that the sounds generated arise from the variation of stress produced by the actuating motion and are instantly available without lag or distortion.

In one of the preferred forms of my invention, I use a double cone of pleated, resilient material possessing a large degree of stiffness and so arranged that the cones may be drawn together and a compression of considerable magnitude set up in their vanes or elements. The force necessary to do this is applied from a point as near as possible to the point of actuation and is there balanced. In this manner the entire system is under stress and, practi-

cally all compressibility and all lost motion having been taken up, is in an energy condition; i. e. is prepared instantaneously to act.

Other and further advantages will appear in the following specification and drawings.

In the drawings:

Fig. 1 is a diagrammatic sectional elevation of a sound generator embodying my invention as applied to a phonograph.

Fig. 2 is an elevation in section of a similar sound generator arranged for electromagnetic operation.

Fig. 3 is a section in elevation of a sound generator arranged for a different form of electromagnetic operation.

In Fig. 1, the sound generator is shown as being of the double cone type; the cones being indicated at 1 and 2. These cones are preferably circular and pleated, the upper edge of the pleats being indicated at 3 and 4 and the lower edges at 5 and 6. The material may be any such as may be capable of being pleated and in addition should possess the qualities of rigidity and resiliency. For this purpose, I have found Japanese yellum satisfactory when impregnated with bakelite although many other substances may be used that have similar characteristics. Cones 1 and 2 have a common meeting edge such as at 7 and this is preferably bound or retained by any suitable means, one of which would be a treated fabric with some ability to stretch, as indicated at 8. The apices of the cones have openings formed by the inner ends of the plates, the opening of the outer cone 9 having a cone shaped member, 9, with a threaded member, 10, and a knurled nut, 11. The opening in the apex of the inner cone fits over the conical member, 12, fixed to the weight or inertia mass, 13. It will be seen that these conical members 9 and 12 practically seal the cones and make them almost air tight; this giving a new result over generators of the old art in which there is an opening. The weight, 13, carries a fulcrum, 14, upon which is seated the lever, 15, which in turn is connected to a rod, 16. Extending between the threaded member, 10, of the upper cone seat and the rod, 16, is a member, 17, made of wire or any other material possessing the requisite strength. Members 16 and 17 may be combined in one piece if desired. Threaded into the weight, 13, and passing through an opening in the lever, 15, is a cap screw, 18, which has a compression spring, 19,

100

105

110

19, acting between it and the lever, so that by means of this screw the pressure of the spring, 19, on the lever, 15, may be varied. Also threaded in a recess of weight, 13, is stop 5 screw, 20, having the usual locking nut and so located as to retain the lever 15 in position when the stress of the system is released. Attached to the lever, 15, and directly in line with the fulcrum 14 is a needle holder, 21, 10 carrying needle, 22, and this needle is retained in the holder by the screw, 23.

By turning the knurled nut, 11, I can increase the tension on the wire, 17, the rod 16 and thus on the lever, 15. To balance 15 this and keep the needle, 22, and its holder in approximately vertical position the cap screw, 18, is turned down until the pressure of spring 19, on that end of lever 15 will balance the tension of the rod, 16, on the other end of 20 the lever. By proper design of the spring, 19, the tension transmitted through the lever, 15, may be made very high, even up to the point of failure of whatever material may 25 compose the cones 1 and 2. In placing a tension on the wire, 17, the vanes or pleats of the cones 1 and 2, are put in a state of compression and this compression, as just stated, may be very widely varied but in general it corresponds to a tension of several pounds on the 30 wire, 17, as low as four and as high as fifty pounds, depending upon circumstances.

When this compression is applied to the cones and the system balanced as just described, it will be seen that while the system 35 is balanced, it is in a state of strain not only in the cones but in the associated elements as well and that this balance of stresses is carried close to the point of actuation; which is the needle, 22. The apparatus just described 40 is one adapted to reproduction of sound from a phonograph record of the type known as lateral cut so that on such records the motion of the needle 22, and its holder, 21, will be an oscillating one about the fulcrum, 14. 45 Therefore, whatever motion is imparted to the needle, 22, will be transmitted to the cones 1 and 2 through the wire, 17, and its associated parts. The vibrations initiated at the needle will then be reproduced as audible sounds by the reproducer or sound generator shown. Where the tension on the wire, 17, is of considerable magnitude and the cones 1 and 2 are in compression and the lever, 15, is in balance, the lost motion of the 50 system is practically eliminated and a large degree of the inherent compressibility of the cone material is taken up and the system is in what may be termed an energy condition so that the slightest movement of needle 22 is 55 instantaneously reproduced without lag and very little energy is absorbed or dissipated.

Another advantage resulting from stressing the system is that the effects of temperature and moisture, which ordinarily create 60 loose areas or otherwise affect the character

istics of the sound generator, become negligible for the reason that whatever changes would ordinarily be brought about by temperature and moisture variations are insignificant in comparison with the magnitude 70 of the compressive stress under which the cones operate, and this is a benefit not found in other devices of like nature. The cones 1 and 2, being ordinarily of pleated construction as heretofore described, may have the 75 individual vanes passing through a 90° twist from each apex to its perimeter, though I prefer to have slightly less torsion than this in the vanes while the device is in an inoperative condition as this permits tuning to the 80 desired pitch. Thus while the vanes at the apex are perpendicular with the edges 1 and 2, they lie in practically horizontal planes at their perimeters. This imparts a degree of torsion in each vane and while not new in the 85 art certain advantages are secured therefrom when used in connection with the compressive stresses.

While I have described a sound generator as being composed of two associated cones, 90 the elements of which are under considerable degree of stress, I have found that the character of this stress is dependent upon the angle which each cone makes its base line, which would naturally be the line of juncture 95 of the cone perimeters as indicated at 24. When this angle is 30° or greater the stress imparted to the cone vanes will be substantially all compression as governed by the tension placed upon the wire, 17. However, 100 when the base angle of the cone is less than 30° and especially at about 15° there will be combined tension and compression; the tension developing near the perimeter of the cone and extending practically one half of 105 the slant height, the remainder being under compression and where this change from tension to compression occurs there will be a neutral point. As the base angle of the cone decreases this neutral point will progress up 110 the slant height until the base angle is in the neighborhood of 10° at which point the cone vanes will be almost entirely under tension. I have found that cones having a base angle 115 of 30° or slightly over, give superior results so that it appears that the compressive 120 stresses are the more important and more satisfactory for the reproduction of sound. However, this relation of compression to tension areas may be modified in the case of 125 double pleated cones having fabric bound perimeters when the fabric has a length somewhat less than the perimeters of the cones so that the angle of the cones is slightly raised. The ratio of compression to tension areas will then be greatly increased and the results improved. If the perimeter binding of the cones is tightened, when the system is otherwise set, the results will be still further 130 improved showing that compressive strains

are more effective and preferable to tension strains. Where a double cone of pleated construction is used as just described, and where the system is under a strain of considerable 5 magnitude which is carried near to the point of actuation, I secure great fidelity of reproduction and brilliance of detail together with great volume, in addition to which there is a very considerable increase in efficiency over 10 what has yet been accomplished. By efficiency I mean a greater response for a given amount of energy. Pleated double cones provide a greater range of action in that there is more give between the apices and as the 15 pitch which can be faithfully reproduced is a function of the area of the sound generator, I find that the pleated double cone can go to much lower limits of pitch and that this pitch can be varied by varying the stress 20 in the system by means of the knurled nut, 11. Therefore I may tune the sound generator to various pitches such as concert or international, and this may be done while the generator is functioning. Another advantage 25 of the double pleated cone is that it is not critical as to pitch but may be easily tuned and retained at that pitch and furthermore, no open bezel is necessary as has heretofore been thought indispensable to procure clarity of tone.

Instead of using the pleated double cone I may use a pleated single cone of similar construction to that of my copending application for sound reproducers, Serial No. 152,091, the 30 perimeter of which would preferably seat upon some strong rigid retaining ring to serve as an abutment for the vanes when under compression. The system would then be balanced under stress as heretofore described. In using such a cone I would secure 35 excellent results but without the range or efficiency of the double cone, added to which is the fact that a single cone is critical as to the adjustment for pitch.

While I have described my system of sound generation as including pleated cones either double or single, I may equally well use plain cones and while the quality of reproduction and the volume would be superior to what is now available, such plain cones would fall short of the quality and volume of reproduction secured from the pleated cones but under certain circumstances I may choose to use cones having plain surfaces.

In my sound reproducers I use a material possessing resiliency and rigidity such as the impregnated Japanese vellum mentioned.

While I prefer to use a relatively light material such as this vellum, I am not limited 60 thereto but may use other and heavier materials with rectangular or trapezoidal pleats (particularly for large cones) as set forth in my copending application for sound reproducers, Serial No. 152,091; it being understood 65 that in the invention of this applica-

tion, the use of stresses of considerable magnitude overcomes the inertia effects as well as providing the benefits and advantages already described. Furthermore, when pleats of trapezoidal shape are used, I secure a better distribution of mass throughout the area 70 of the sound generator and also in relation to the stress. The small ends of the trapezoids being at the center, there is a smaller mass at that point and a better and less clumsy 75 connection to the rest of the system is possible.

In Fig. 2 is shown my system of sound generation adapted to use with an electromagnetic actuating unit. The pleated cones are 80 shown at 25 and 26 with the upper edges or ridges of the pleats shown at 27 and 28, and the lower edges at 29 and 30; the perimeters being joined as indicated by the line 31. In like manner to Fig. 1 the outer apex of cone 85 25 has a cone seat, 32, through which passes the threaded piece, 33, carrying the knurled nut, 34. The apex of the inner cone, 26, also seats upon a cone, 35, fixed to the unit, 36. Fixed to the threaded member, 33, and passing 90 through openings in the cone seat, 35, and the frame of the unit, 36, is a wire or tension element, 37. This wire, 37, is affixed to the lever, 38, seated upon the fulcrum, 39, as shown. The lever, 38, has an opening through 95 which passes the cap screw, 40, threaded into the frame of the unit, 36, and upon which is mounted a compression spring, 41, acting between the head of the cap screw and the lever. At the opposite end of the lever from 100 this cap screw is a screw, 42, which serves to retain the rod or wire, 43, in an opening provided in the lever. The wire, 43, is fastened to the oscillating member, 44, pivoted at 45. The unit, 36, has its usual frame, 46, carrying 105 pole pieces 47 and 48 and the field coils, 49.

This adaptation of my sound generating system utilizes the same principles as described under Fig. 1. The knurled nut, 34, provides an adjustable means for creating 110 compression in the vanes of the pleated cones, 25 and 26, and this compression may be brought up to the point of the strength of the cone material and the tension upon the wire, 37, is balanced at the lever, 38, by the spring, 115 41, which is itself adjustable by means of the cap screw, 40. Consequently there is again a balanced system obtained with the cones in the required degree of compression, the wire, 37, in tension and all being balanced in the 120 lever, 38. The actuation of the system takes place from the oscillation of the member, 44, as caused by the field coil, 49, in conjunction with the pole pieces. This actuation is imparted to the lever, 38, by the wire, 43. It will 125 be noticed that the only neutral portion of the entire apparatus is that which includes the member, 44, and the wire, 43, and this is maintained in a neutral condition by setting the screw, 42. Therefore, not only is the whole 130

system under stress but that stress is brought close to the point of actuation and, as heretofore described, there is an energy condition wherein all lost motion and inherent compressibility or elasticity is taken up, and energy imparted to the system from the unit will be all used in creating vibrations in the cones by varying the stress therein.

I have heretofore described the material composing, and the formation of, these cones which included the desirability of light weight to avoid inertia effects. To this end the cone seat, 32, of Fig. 2, as well as seat 9 of Fig. 1, are made of any suitable material, and the tension means attached to them are preferably wire or rods of a size sufficient to withstand the tension placed upon them.

In Fig. 3 is a further adaptation of my system to an electromagnetic unit wherein the actuating energy is applied directly instead of through a lever as in Figures 1 and 2. It is customary in phonographic and in electromagnetic units to have the arms of the lever in the reducing ratio of about 2/3 to 1, and this has become more or less standard. Attempts have been made to apply the actuating energy directly to the sound generator but heretofore such disadvantages have appeared as to make this commercially unsuccessful. However, I have found that a structure such as indicated in Fig. 3, successfully accomplishes this result with equal if not greater benefits than the lever construction shown in the previous figures. To this end cones 50 and 51 are constructed and joined as heretofore described. The upper cone has a similar cone seat, 52, a knurled nut, 53, carried by threaded member, 54. The lower cone rests upon cone 55 of the unit. This unit is of the type known as jump coil wherein the frame and pole pieces are at 56, the field coils at 57, and the jump coil at 58; this jump coil being spanned by the yoke, 59. The unit has a hollow central portion in which is seated the cap, 60, carrying the threaded member, 61, and a compression spring seated in the hollow portion. Extending between the threaded members, 54 and 61, and fastened thereto is the wire or tension member, 62, which not only passes through the unit as shown but is fixedly attached at 63 to the yoke, 52, of the jump coil. As already stated the cones may be placed under as much compression as desired and the tension set up in the wire, 62, is balanced by the spring acting against the threaded member, 61, so that the jump coil, 58, will be carried directly on the wire, 62. Here it will be seen that stresses set up in the system are not only balanced but are led directly to the point of actuation which is at 63. Consequently, when in operation whatever movement occurs in the jump coil, 58, is imparted directly to the cones, 50 and 51. Here there is no lost motion whatever to be taken up and the cones having been placed in an initial en-

ergy condition, the reproduction in this system will be equal to if not superior to the two systems previously described.

From the foregoing it is clear that my invention covers a principle not yet known or used by others nor taught by the prior art and it is essentially one of creating high initial stress in the sound generator, and carrying that stress near or to the point of actuation and there balancing it; the sound production being a result of variations in the stress caused by the actuator.

I am aware that many changes and modifications may be made in my invention without departing from the spirit thereof and I include all such changes and variations within the scope of my claims.

I claim:—

1. A system of sound generation which comprises a sound generator under compressive stress, means to create that stress and other means to balance the stress creating means. 85

2. A system of sound generation which comprises a sound generator under compressive stress, means to create that stress, an actuating unit and means to balance said stress creating means close to the point of actuation in said unit. 90

3. A system of sound generation comprising a double cone under compressive stress, means to adjust that stress and means to actuate said cones by varying the stress therein. 95

4. A system of sound generation which comprises a sound generator and an actuating unit, adjustable tension means arranged to create compressive stresses in said generator and means within the unit to balance said tension means. 100

5. A system of sound generation which includes a sound generator and an actuating unit, adjustable tension means acting between said generator and said unit, and adapted to set up compressive strains in said generator and means to actuate said generator by actuating said tension means. 105

6. A system of sound generation wherein sounds are generated by varying the stress in a sound generator initially under compressive stress. 115

7. A system of sound generation wherein sounds are generated by varying the stresses in a sound generator initially under compressive and torsional stresses. 115

8. A system of sound generation which includes a hollow sound generator, means to create a compressive stress in the walls of said generator and means to generate sound by varying said stress. 120

9. A system of sound generation which includes a pleated, hollow sound generator, the elements of which are maintained under compression. 125

10. A system of sound generation including a double cone sound generator from the 130

apex of one of which a tension is created, an actuating unit and means associated with said unit to balance said tension.

11. A system of sound generation which includes a sound generator in which compressive stresses of considerable magnitude are created by tension means and other means directly to actuate said tension means.

12. A system of sound generation which includes a sound generator in which compressive stresses of considerable magnitude are created by tension means, means to balance said tension and means to actuate said tension means.

13. A system of sound generation, which includes a pleated sound generator having torsional stresses in the pleats, tension means coacting with and adapted to set up compressive stresses of considerable magnitude in said generator, means to balance the tension of said tension means and means to actuate the tension means.

14. A system of sound generation which includes a double cone sound generator and an actuating unit, adjustable means arranged to cause the apices of said cones to approach each other, means associated with said unit

to balance the adjustable means and other means within the unit to actuate the balancing means.

15. A system of sound generation which includes a cone sound generator having a rigidly supported perimeter, an actuating unit, adjustable tension means acting between the apex of said cone and said unit, means associated with said unit to balance said tension means and other means associated with said unit to actuate said tension means.

16. The method of generating sound which comprises placing a body under compressive stress of considerable magnitude and then varying that stress.

17. The method of generating sound which comprises placing a body under compression by applying a tension to a selected point of said body and then varying said tension.

18. The method of generating sound which comprises placing a body under torsional and compressive stresses and then varying said stresses.

In witness whereof, I have hereunto subscribed my name this 30th day of November, 1927.

CHARLES P. MADSEN.
